UNITED STATES PATENT OFFICE

THOMAS F. KELLY, OF CLINTON, IOWA, ASSIGNOR OF ONE-HALF TO JOSEPH A. KELLY,
OF CLINTON, IOWA.

CONVERTIBLE FURNITURE.

1,318,285.

Specification of Letters Patent.

Patented Oct. 7, 1919.

Application filed February 4, 1919. Serial No. 274,931.

To all whom it may concern:

Be it known that I, THOMAS F. KELLY, a citizen of the United States, residing at Clinton, in the county of Clinton and State of Iowa, have invented a new and useful Convertible Furniture, of which the following is a specification.

This invention relates to convertible furniture of that type better known as a bed davenport, and is designed, primarily, as an improvement upon the structure disclosed in Patent Number 1,276,227 issued to William J. Kelly on August 20th, 1918.

Heretofore, in the construction of devices of this character, it has been the practice to limit the relative movement of certain of the sections, during the operation of opening the bed, by providing chains which connect the said sections and become taut when the sections come into alinement, holding the sections in alinement until the legs or supports come into contact with the floor. These chains have been found to be objectionable for several reasons. First, while the bed is being opened the intermediate and outer movable sections thereof, on passing the center of gravity, will move suddenly relative to each other until they come into alinement whereupon they will be brought to an abrupt stop by the chains. This often causes the chains to break or to tear their fastenings from the sections. It also imparts an objectionable jolt to the arms and body of the person opening the bed. A second objection is found in the fact that the chains, at times, become twisted and will not allow the sections to move into alinement. A further objection is that it becomes necessary, when closing the bed, to swing the movable sections upwardly to a substantially vertical position before folding them toward each other, in order to allow the slack chain to drop into proper position within the intermediate section of the bed.

The present invention has for an object the elimination of the foregoing objectionable feature, by providing a novel form of cushioning element between the movable sections of the bed and which yieldingly resists the complete opening of the bed, so as thus to eliminate the objectionable jarring of the body and the danger of breaking any of the parts as a result of the sudden stopping of the relative swinging movement of the sections. A further object is to provide a

cushioning connection of this character which becomes slightly slack when the bed is fully extended to active position upon the floor and which allows the operator, when closing the bed, to first lift only the outer end section after which the connection will when drawn taut, pull upon and lift the intermediate section, the gradual increase in the weight being lifted by the operator, rendering the structure easier to close than would be the case should it be necessary to lift the entire weight of the two movable sections at the beginning of the closing operation. Another object is to so arrange the connection that, when the movable sections are brought to a certain elevation during the closing operation, they will be shifted automatically relative to each other so as to close easily and accurately into the frame of the structure.

With the foregoing and other objects in view, which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention as set forth in the appended claims.

In the accompanying drawings the preferred form of the invention has been shown.

In said drawings—

Fig. 1 is a vertical longitudinal section through the bed davenport extended or unfolded for use as a bed.

Fig. 2 is a rear elevation of the structure with the back removed and the parts positioned for use as a davenport.

Fig. 3 is a plan view of the structure extended, parts being removed.

Fig. 4 is a detail view of the yieldable connection in the position assumed thereby when the bed is extended for use.

Fig. 5 is a similar view showing the same in the position assumed after the first stage of the lifting operation, while closing the bed.

Fig. 6 is another like view showing the connection as it appears when the bed is closed for use as a davenport.

Referring to the figures by characters of reference, A designates the housing or main

105

110

structure of the article, the same being provided with a stationary bottom section B to the front of which is hingedly connected a movable intermediate section C. An end 5 movable section D is hingedly connected to the section C and when the article is used as a davenport, the section C constitutes the seat while the section D extends upwardly therefrom and forms the back. Both of 10 these movable sections are provided with cushions, as shown at E and, when the device is extended for use as a bed, the said cushions are supported underneath them, as shown. The side rails of the sections C and 15 D are cut away at those ends thereof hingedly connected, thus to allow the section D to assume an upstanding position when the article is used as a davenport. A metal fabric bed bottom is arranged within and 20 secured to the sections B, C and D, as shown at F and will be completely housed by said sections when folded. The sections C and D are provided with legs G for supporting them when extended.

25 The structure heretofore described has already been disclosed in the patent hereinbefore mentioned and does not, in itself, constitute any part of the present invention. The present improvements include 30 opposed pairs of rods or links 1 and 2, the links 1 of each pair being connected by eye bolts 3 or the like, to a cross rail c forming a part of the section C and located near the hinge connection H between the two sections C and D. The other links 2 of each 35 pair are similarly connected to a cross rail d forming a portion of the section D and located near the hinge connection H. The links 1 and 2 of each pair are pivotally 40 connected to a plate 3 or the like which may be provided with a hooked tongue 4 and the tongues of the two plates engage the ends of a coiled spring 5 which is constantly under tension. The links 1 and 2 and the 45 plates 3 are so proportioned that, when the sections C and D are in alinement while in use as a part of the extended bed, the said links of each pair will be pulled out of line by the spring as shown in Fig. 4, and the 50 entire weight of the bed sections C and D will be supported by the legs G. When it is desired to fold the device the user takes hold of the front edge of the section D and pulls upwardly. This causes said section 55 to swing upwardly relative to the section C at the connection H and as the rails c and d are located below the level of the hinge connection H, such relative movement will continue until it causes the links of each pair 60 to move into line against the action of the spring whereupon the intermediate section C will also move upwardly. After the two sections C and D have been raised a certain distance to relieve the spring 5 of the restraint due to pressure against the section D,

the spring 5 will come into play and move the links 1 and 2 from the positions shown in Fig. 5 and cause them to draw together, as shown in Fig. 6, thereby pulling the rails c and d toward each other and forcing the 70 sections C and D to move out of line and to assume positions to form the seat and back of the davenport, when brought into the housing structure A. Thus it will be seen that the links operate as toggle connections 75 yieldingly restrained in their actions by the single spring connecting them.

What is claimed is:—

1. The combination with a main structure, a stationary section therein, a movable end section, and an intermediate section hingedly connected to the stationary and end sections, said sections being shiftable into alinement to form an extended bed, of means for automatically folding the end and intermediate sections when raised out of extended position and for allowing a limited independent upward movement of the end section when the structure is extended, said means including toggles connecting the intermediate and end sections, and an elastic connection between the toggles. 80

2. In a device of the character described the combination with a stationary section, an intermediate section hinged thereto and 95 adapted to swing outwardly therewith, and an outer end section hinged to the intermediate section and adapted to swing downwardly relative thereto, of spring controlled means for limiting the upward movement of the outer section relative to the inner section, transmitting motion to the intermediate section from the outer section, and for facilitating the movement of said outer section in the opposite direction relative to the intermediate section. 100

3. In a device of the character described the combination with a stationary section, an intermediate section hinged thereto and adapted to swing thereonto and outwardly 110 therewith, and an outer end section hinged to the intermediate section and adapted to swing into alinement therewith when unfolded and into upwardly extended or back-forming position when folded, of yieldingly 115 controlled means connected to the outer and intermediate sections, and below their hinges when the device is extended or unfolded for limiting the upward swinging movement of the end section relative to the intermediate section when in extended position for transmitting motion from the outer section to the intermediate section and for exerting a folding action upon said sections when raised out of extended position. 120

4. In a device of the character described the combination with a stationary section, an intermediate section hinged thereto, and an outer section hinged to the intermediate section, said sections being shiftable into 125

alinement to form a bed and being foldable to form a davenport seat, of toggles connecting the end and intermediate sections below the plane of the hinge connections when the device is extended, a spring connecting the toggles to hold the toggle links out of alinement when the device is extended, said spring and toggles coöperating to facilitate the folding of the device when raised out of 10 extended position.

5. In a device of the character described the combination with hingedly connected sections, of toggles connecting the sections for transmitting motion from one section 15 to the other during the raising of the sections, and a spring connecting the toggles to hold them yieldingly under restraint during the raising of the sections and to fold the toggles and the sections when the sec-

tions are raised past a predetermined point, 20 said spring being movable to position parallel with and in juxtaposition with the adjoining edges of said sections when folded.

6. In a device of the character described the combination with hingedly connected 25 sections, of means for resisting the movement of the sections into alinement and for facilitating the folding of the sections, said means comprising toggles connecting the sections at their hingedly connected ends, 30 and a spring connecting the toggles, said spring and toggles being disposed in a plane extending past and below the hinge connections when the device is unfolded or extended.

In testimony that I claim the foregoing as my own I have hereto affixed my signature.

THOMAS F. KELLY.
